DISTRIBUTING APPARATUS

Horace Lowe, Eastport, Maine, assignor to Riviera Packing Company, Eastport, Maine, a partnership composed of Victor N. Cory and Arnold Vogl

Application November 10, 1945, Serial No. 627,916

4 Claims. (Cl. 198—30)

1

This invention relates to a distributing apparatus—more particularly to a device for distributing units, such as cans or containers, from one conveyor production line to a plurality of subsequent conveyor lines.

One of the applications of this invention is in the canning industry, where open cans are filled or otherwise treated while traveling along one or more conveyor belts, and then alternately directed along different paths towards closing machines.

It is within the contemplation of this invention to provide an efficient apparatus of the above-mentioned category, and capable of automatically distributing each of several lines of conveyor-carried units alternately to different paths, without disturbing or in any way interfering with the travel of the conveyor belts.

And it is another object of this invention to enable a relatively simple mechanical device to effect the aforesaid distribution and the alternate changes in the path of travel of lines of units continuously and without interruption.

Other objects, features and advantages will appear from the drawings and the description hereinafter given.

Referring to the drawings.

Figure 1 is a fragmentary plan view of the apparatus of my invention;

Figure 2 is a fragmentary side of the elevation thereof; and

Figure 3 is a section of Figure 1 taken substantially along line 3—3.

In the particular embodiment of my invention shown in the drawings, there are two lines of cans 10 and 11 traveling in the direction of the arrow on the conveyor system 12, being preferably a single belt extending along the width of the apparatus. The invention is not, however, limited to a single belt, nor to two production lines, inasmuch as a plurality of parallel belts and one or many production lines may be employed, if desired, within the scope of the invention. Flanking each line of cans along their respective paths are the stationary side rails 13 and 14, and 15 and 16, whereby the cans are maintained along their operative paths. Attached by hinges 17 to said stationary rails are the gate guides 18, 19, 20 and 21, respectively. Each of these guides is movable, by means to be hereinafter described, between two limiting positions shown by dot-dash lines, whereby the discharge positions of the cans are changed so that they may be directed to different paths, as will hereinafter appear.

2

The conveyor belt 12 continues past the terminals of gate guides 18, 19, 20 and 21, its width being thereafter in region generally designated A, divided into four paths 22, 23, 24 and 25 formed by the stationary longitudinal side rails 26, 27, 28, 29 and 30. The said gate guides 18, 19, 20 and 21 are so actuated that the line of cans 10 will be directed from path 10a alternately to paths 22 and 23, and the line of cans 11 will be directed from path 11a alternately to paths 24 and 25. During this action the terminals of gate guides 18, 19, 20 and 21 are alternately brought into substantial longitudinal alignment with the side rails in region A forming the corresponding longitudinal paths.

The preferred form of mechanism for operatively actuating the gate guides 18, 19, 20 and 21 comprises a gate spacer 31 for each pair of guides that form a path, connected by bolt 32 to arm 33. Each of said arms is in slidable engagement with bracket 34 which is secured to transverse slide bar 35. The latter is slidably supported by cross member 36 suitably affixed to uprights 37. The said slide bar 35 extends beyond the guide channels 38 supported by uprights 37, the legs 39 of the channels being in slidable engagement with the said slide bar 35. The terminal portion 40 of the slide bar is connected to the follower member 41 consisting, in the form illustrated, of a post 42 and roller 43 disposed within the channelled groove 44 of the cam wheel 45. The said groove 44 has an inner portion 46 thereof disposed closer to the conveyor than the outer portion 47, the difference in the respective distances to the conveyor of said two portions representing the operative throw of the cam, or the operative movement of the slide bar 35 and connected parts. In the preferred form of my invention, one-half of the operative path of groove 44 consists of portion 46, and one-half of portion 47, whereby for each revolution of the cam wheel 45 there will be one inward and one outward movement of slide bar 35 resulting in one alternation of the production lines per revolution of the cam.

In the form illustrated, each arm 33 is held secured to the bolt 32 by nut 48, and is pivotally connected to the gate guides, such as 18 and 19, by the fasteners 49. Each of said arms 33 is also slidably supported by transversely extending rest bar 50. The arrangement is such that upon an operative movement of the slide bar 35, the arms 33 will not only actuate the gate guides 18, 19, 20 and 21, but will also slidably move longitudi-

dinally of the apparatus because of the arcuate path of bolt 32.

In the operation of this apparatus, a simple rotary movement of the cam wheel 45, connected by shaft 51 to a source of motive power not shown, will thus operatively oscillate the gate guides 18, 19, 20 and 21 and thereby alternately divert each of the lines of cans 10 and 11 in different paths. And this is accomplished without interfering with or interrupting the continuity of movement of conveyor belt 12.

It is understood that the embodiment above described and shown in the drawings is merely illustrative of my invention, and that numerous changes and modifications may be made therein, within the scope of the appended claims without departing from the spirit of this invention.

I claim:

1. In a distributing apparatus having a pair of rearwardly hinged gate guides the forward portions of which are movable between two predetermined limiting positions, the combination of a transversely disposed spacer pivotally connected to the said forward portions of the gate guides, a longitudinally disposed actuating arm pivotally connected to said spacer, a rest support underlying the arm for slidably supporting the arm during its operative movements, a transversely disposed slide bar connected to said arm for actuating it laterally, guiding means in slidable engagement with said slide bar for holding it along its operative path, a rotary cam wheel, and a reciprocating cam follower member operatively connected to said cam wheel and said slide bar for reciprocatingly actuating the bar, whereby the gate guides will be operatively oscillated between said limiting positions.

2. In a distributing apparatus having a pair of rearwardly hinged gate guides the forward portions of which are movable between two predetermined limiting positions, the combination of a transversely disposed spacer pivotally connected to the said forward portions of the gate guides, a longitudinally disposed actuating arm, perforated portions in said spacer and arm, a bolt extending through said perforated portions and pivotally connecting the said arm to the spacer, a transversely disposed slide bar connected to said arm for actuating it laterally, supporting means for said slide bar, a rest support underlying the arm for slidably supporting the arm during its operative movements, guiding means supported by said supporting means and in slidable engagement with said slide bar for holding it along its operative path, a rotary cam wheel, and a reciprocating cam follower member operatively connected to said cam wheel and said

slide bar for reciprocatingly actuating the bar, whereby the gate guides will be operatively oscillated between said limiting positions.

3. In a distributing apparatus having a pair of pivotally mounted guide members movable between two predetermined limiting positions, the combination of a spacer member pivotally connected to both of said guide members whereby the members are operatively maintained in parallel relation, a longitudinally disposed arm pivotally connected to the spacer member, a transversely disposed slide bar connected to said arm for actuating it laterally, a rotary cam wheel, and a reciprocating cam follower member operatively connected to said cam wheel and said slide bar for reciprocatingly actuating the bar, whereby the guide members will be operatively oscillated between said limiting positions, said cam wheel containing thereon a channelled grooved cam path, the follower member being operatively disposed within said groove.

4. In a distributing apparatus having a pair of pivotally mounted guide members movable between two predetermined limiting positions, the combination of a spacer member pivotally connected to both of said guide members whereby the members are operatively maintained in parallel relation, a longitudinally disposed arm pivotally connected to the spacer member, a transversely disposed slide bar connected to said arm for actuating it and the associated members, whereby the guide members will be operatively oscillated between said limiting positions, a cam means containing a rotatably mounted cam wheel containing thereon a channelled groove cam path, the axis of rotation being substantially parallel to the slide bar, the said cam path being peripherally disposed on the cam member, and a follower member operatively disposed within said groove and connected to said slide bar, said path containing predetermined inner and outer portions for operatively imparting a predetermined movement to the slide bar.

HORACE LOWE.
